UNITED STATES PATENT OFFICE

ROY CROSS, OF KANSAS CITY, MISSOURI, ASSIGNOR, BY MESNE ASSIGNMENTS, TO GASOLINE PRODUCTS COMPANY, INC., OF WILMINGTON, DELAWARE, A CORPORATION OF DELAWARE

PROCESS AND APPARATUS FOR CONVERSION OF HYDROCARBON OILS

Application filed September 30, 1926. Serial No. 138,806.

This invention relates to improvements in a process and apparatus for the conversion of hydrocarbon oils, and refers more particularly to a process for the cracking of relatively 5 heavy oils into lighter oils having the characteristics of gasoline or the like.

Among the objects of the invention are to provide a process in which a cracking stock is heated to a conversion temperature in the 10 heating zone and is thence passed to a reaction chamber of an enlarged cross sectional diameter relative the heating zone, wherein the temperature is maintained substantially the same as that arrived at in the heating zone, in 15 order to continue the cracking instituted in the furnace or heating coil; to provide a process in which the oil, after passing through the reaction zone, is cooled and an oxidizing gas introduced thereto to increase the formation 20 of certain desirable hydrocarbon derivatives having characteristics which improve the anti-detonating qualities of the finished motor fuel; to provide a process in which subsequent to the introduction of an oxidizing gas 25 the oil products are passed to a zone of reduced pressure and there vaporized, the vapors being subjected to a refluxing action and final condensation while certain of the heavier products are returned for retreat- 30 ment in the system, and in general to provide a process hereinafter described.

The single figure is a side elevational view with parts in section and parts broken away.

At 1 in the drawing is shown a furnace, 35 consisting of a combustion chamber 2 and a tube compartment 3. The furnace is preferably heated by means of gas burners, not shown, positioned adjacent to, or in the combustion compartment, the combustion gases 40 passing from the combustion compartment into the tube chamber containing a continuous coil 4, and discharged from the bottom of the tube chamber through a flue 5. The discharged end of the tubes 4 is connected by 45 a line 6 to the reaction chamber 7, which is preferably formed from a single ingot of forged steel and heavily insulated to prevent loss of heat by radiation. End openings, affixed to the reaction chamber, are removable 50 to facilitate the cleaning of the chamber.

The heating coil 4, fittings and connections, together with the reaction chamber are of materials adapted to withstand high pressures and high temperatures. The opposite end of the reaction chamber has communication through a pipe 8 to a cooling or oxidizing zone 9, which is also constructed of heavy material to withstand pressures similar to those maintained in the heat and reaction chamber. This retort 9 has removable end plates to assist in the cleaning thereof, and also in making replacement or repairs of apparatus contained in the retort. 55

Within both the reaction chamber and the retort 9 are perforated pipes 10 and 11 respectively. Two compressors 12 and 13 have connections with the perforated pipes by means of the lines 14, 15 and 16. A line 17 connects the pipe 16 with the line 14, so that introduction of materials may be made from 60 either compressor to either of the perforated pipes 10 or 11. The retort 9 has connection with an evaporator 18 through a transfer line 19, controlled by a reduction valve 20. The top of the evaporator has a vapor line 70 connection 21 with the dephlegmating tower 22, which in turn has a vapor line connection 23 with the condenser coil 24 positioned in the condenser box 25. The discharge end of the condenser coil terminates in a line 26 which 75 leads to the gas separator 27. This gas separator has an upper gas relief line 28 controlled by a valve 29, and a liquid level draw-off line 30, regulated by a valve 31.

A draw-off line 32 connected into the bottom of the evaporator is controlled by a valve 33 manipulated by an automatic liquid level regulating mechanism diagrammatically shown at 34. The draw-off line 32 leads to a cooler 35 where the bottoms withdrawn from 80 the evaporator are cooled before being directed to storage to the line 36. A similar draw-off line 37, connected into the bottom of the dephlegmator 22, is controlled by a valve 38, the latter being manipulated by an automatic liquid level regulating device 39, similar to that shown at 34. The line 37 directs the recycled stock or refluxed condensate to a tank 40, from which it may be diverted from 85 the system through a line 41, controlled by 90 valve 42. The line 41 connects to the bottom of the tube compartment 3, so that the recycled stock may be returned to the system. The line 41 is controlled by valve 43. The line 44 connects the tube compartment 3 to the bottom of the reaction chamber 7, so that the cracked vapors may be introduced into the reaction chamber. The line 44 is controlled by valve 45. The line 46 connects the bottom of the reaction chamber 7 to the bottom of the tube compartment 3, so that the cracked vapors may be introduced into the tube compartment. The line 46 is controlled by valve 47. The line 48 connects the bottom of the tube compartment 3 to the bottom of the reaction chamber 7, so that the cracked vapors may be introduced into the reaction chamber. The line 48 is controlled by valve 49. The line 50 connects the bottom of the reaction chamber 7 to the bottom of the tube compartment 3, so that the cracked vapors may be introduced into the tube compartment. The line 50 is controlled by valve 51. The line 52 connects the bottom of the tube compartment 3 to the bottom of the reaction chamber 7, so that the cracked vapors may be introduced into the reaction chamber. The line 52 is controlled by valve 53. The line 54 connects the bottom of the reaction chamber 7 to the bottom of the tube compartment 3, so that the cracked vapors may be introduced into the tube compartment. The line 54 is controlled by valve 55. The line 56 connects the bottom of the tube compartment 3 to the bottom of the reaction chamber 7, so that the cracked vapors may be introduced into the reaction chamber. The line 56 is controlled by valve 57. The line 58 connects the bottom of the reaction chamber 7 to the bottom of the tube compartment 3, so that the cracked vapors may be introduced into the tube compartment. The line 58 is controlled by valve 59. The line 60 connects the bottom of the tube compartment 3 to the bottom of the reaction chamber 7, so that the cracked vapors may be introduced into the reaction chamber. The line 60 is controlled by valve 61. The line 62 connects the bottom of the reaction chamber 7 to the bottom of the tube compartment 3, so that the cracked vapors may be introduced into the tube compartment. The line 62 is controlled by valve 63. The line 64 connects the bottom of the tube compartment 3 to the bottom of the reaction chamber 7, so that the cracked vapors may be introduced into the reaction chamber. The line 64 is controlled by valve 65. The line 66 connects the bottom of the reaction chamber 7 to the bottom of the tube compartment 3, so that the cracked vapors may be introduced into the tube compartment. The line 66 is controlled by valve 67. The line 68 connects the bottom of the tube compartment 3 to the bottom of the reaction chamber 7, so that the cracked vapors may be introduced into the reaction chamber. The line 68 is controlled by valve 69. The line 70 connects the bottom of the reaction chamber 7 to the bottom of the tube compartment 3, so that the cracked vapors may be introduced into the tube compartment. The line 70 is controlled by valve 71. The line 72 connects the bottom of the tube compartment 3 to the bottom of the reaction chamber 7, so that the cracked vapors may be introduced into the reaction chamber. The line 72 is controlled by valve 73. The line 74 connects the bottom of the reaction chamber 7 to the bottom of the tube compartment 3, so that the cracked vapors may be introduced into the tube compartment. The line 74 is controlled by valve 75. The line 76 connects the bottom of the tube compartment 3 to the bottom of the reaction chamber 7, so that the cracked vapors may be introduced into the reaction chamber. The line 76 is controlled by valve 77. The line 78 connects the bottom of the reaction chamber 7 to the bottom of the tube compartment 3, so that the cracked vapors may be introduced into the tube compartment. The line 78 is controlled by valve 79. The line 80 connects the bottom of the tube compartment 3 to the bottom of the reaction chamber 7, so that the cracked vapors may be introduced into the reaction chamber. The line 80 is controlled by valve 81. The line 82 connects the bottom of the reaction chamber 7 to the bottom of the tube compartment 3, so that the cracked vapors may be introduced into the tube compartment. The line 82 is controlled by valve 83. The line 84 connects the bottom of the tube compartment 3 to the bottom of the reaction chamber 7, so that the cracked vapors may be introduced into the reaction chamber. The line 84 is controlled by valve 85. The line 86 connects the bottom of the reaction chamber 7 to the bottom of the tube compartment 3, so that the cracked vapors may be introduced into the tube compartment. The line 86 is controlled by valve 87. The line 88 connects the bottom of the tube compartment 3 to the bottom of the reaction chamber 7, so that the cracked vapors may be introduced into the reaction chamber. The line 88 is controlled by valve 89. The line 90 connects the bottom of the reaction chamber 7 to the bottom of the tube compartment 3, so that the cracked vapors may be introduced into the tube compartment. The line 90 is controlled by valve 91. The line 92 connects the bottom of the tube compartment 3 to the bottom of the reaction chamber 7, so that the cracked vapors may be introduced into the reaction chamber. The line 92 is controlled by valve 93. The line 94 connects the bottom of the reaction chamber 7 to the bottom of the tube compartment 3, so that the cracked vapors may be introduced into the tube compartment. The line 94 is controlled by valve 95. The line 96 connects the bottom of the tube compartment 3 to the bottom of the reaction chamber 7, so that the cracked vapors may be introduced into the reaction chamber. The line 96 is controlled by valve 97. The line 98 connects the bottom of the reaction chamber 7 to the bottom of the tube compartment 3, so that the cracked vapors may be introduced into the tube compartment. The line 98 is controlled by valve 99. The line 100 connects the bottom of the tube compartment 3 to the bottom of the reaction chamber 7, so that the cracked vapors may be introduced into the reaction chamber. The line 100 is controlled by valve 101.

a valve 42, or returned and recycled through the system by means of a pipe 43, communicating with the suction side of the pump 44, which discharges through the line 45 to the 5 heating coil.

Fresh charging stock is supplied to the system through the line 46 and pump 47, being either directed through the heat exchanging coil 48, positioned within the retort 10 9, through which the hot oil is being circulated, or through the by-pass line 49, or regulated quantities through both the pipes 48 and 49 to secure the desired degree of cooling of the oil passing through the retort 9. 15 This control of the quantity of the stock passing through the retort as a cooling medium is regulated by valves 50 and 51.

In operation charging stock is supplied, as suggested, from any convenient source 20 through the pipe 46, and is charged by means of the pump 47, through the line 52 and thence either through the coil 48, positioned in the retort 9, or a portion through the coil and a portion through the by-pass line 49. 25 These lines unite to form the pipe 53, which directs the oil to the heating coil 4. In the heating zone the oil is brought to a conversion or cracking temperature, the velocity of circulation being so regulated as to prevent accumulation of carbon in the tubes. The heating is also regulated to the extent that sufficient heat will be added to the oil to continue the cracking, or conversion when the oil is passed on to the reaction chamber. 30

35 In the reaction chamber the oil is collected in a considerable body and due to the high temperature conversion is continued. In order to maintain the desired cracking temperature there may be added in this stage 40 a gaseous material, which combines with the hydrocarbon by exothermic combination. Such gases as oxygen or air, added to the reaction stage by means of a compressor 12, through the line 14, and perforated pipe 10

45 would produce this result. Operating conditions must be regulated, however, so that the introduction of gaseous material at this high temperature and pressure does not produce the combination of objectionable materials, 50 such as water vapor. Applicant has found that in this process the production of moisture at these high temperatures and pressures is objectionable on account of the fluctuation of operating conditions produced by the existence of the water vapor in the system. Furthermore it has been found from actual operation that due to the reactivity of the oil at the temperature and pressures of the reaction stage it is better to reduce somewhat the 55

60 temperature of the oil before the injection of gaseous materials which produce in the oil body anti-knock or anti-detonating properties of the ultimate distillate. Such material, as the alcohols, ketones and other products resulting from the introduction of oxi-

dizing vapors, can be better formed at the temperatures to which the oil is brought in the retort 9 by cooling with the circulation of the charging stock through this stage to reduce the temperature of the oil to the extent that the combination of the gaseous material with the oil is more satisfactorily effected. For this reason connections are made with the compressor 13 and with the 70 perforated pipe 11 so that the gaseous material may be injected into the retort 9, through which oil is passed at a temperature somewhat lower than the temperature maintained in the reaction chamber. At the point of discharge from the oxidizing zone 9 the 75 pressure is released and the oil introduced into the evaporating stage where immediately a separation into vapor and liquid takes place, due to the reduction of pressure and the contained heat in the oil. 80

The vapors passing overhead from the evaporator are subjected to a dephlegmating or refluxing action in the tower 22, which is preferably of the bubble type construction, the refluxed vapors passing off from the top 85 of the dephlegmator through the line 23 to the condenser 25, thence to the gas separator 27. The gas removed through the line 28 may be further stripped or used direct in the burners of the furnace for fuel purposes. The liquid distillate is drawn off from the 90 bottom of the gas separator.

If it is necessary to reduce the temperature of the oil in the retort 9 to the extent 100 that satisfactory evaporation is not effected by the reduction of pressure on its introduction into the evaporating stage, this stage may be heated by the injection of steam, either super-heated or otherwise through the pipe 54. The bottoms from the evaporator as explained are cooled and directed to storage while the refluxed condensate drawn off from the dephlegmating tower is diverted 105 from the system, or recycled.

As typical of the operating conditions, oil charged to the furnace is heated to temperatures ranging from 800° to 1050° F., while pressures of from 500 to 2000 pounds per square inch are maintained upon the oil undergoing treatment. Any temperature drop in the reaction chamber will be produced wholly by the endothermic action of cracking or by loss of heat through radiation. As suggested, this temperature may be maintained by the introduction of oxidizing gases. The oil is cooled in the retort 9 to temperatures ranging from 350° to 600° F. depending upon the oil undergoing treatment and the gas introduced in this zone. 115

The pressure on the oxidizing zone or the retort 9 may be substantially that of the heating coil, and reaction chamber, or it may be reduced somewhat by manipulation of the valve 55 in the line 8. The temperature in the evaporating stage will vary according to 120 125 130

- the temperatures in the preceding stages, but will in all events be considerably less, due to the loss of heat by vaporization. The purpose of the cooling, or oxidizing zone is to drop the temperature to that point where excessive reaction will not occur, or the reaction will be limited to the extent that the desired products will be produced rather than objectionable water and precipitated carbon.
- 5 It has been found from actual experimentation that oxygen when introduced into the hydrocarbon molecule combines more readily to produce desirable properties in the gasoline at lower temperatures, such as temperatures ranging from 350° to 700° F. The oil in the oxidizing zone is cooled preferably by heat exchange with the charging stock, and in place of a single zone, as shown, the heat exchange may be made in a double pipe arrangement with the injection of the gaseous materials effected in a separate retort or chamber. The desirable products produced in the ultimate distillate by the introduction of air or other oxygen bearing gas
- 10 are certain hydrocarbon derivatives of the nature of acetone, aldehydes, organic esters, organic acids and the like.
- I claim as my invention:
1. In an apparatus for converting hydrocarbon oils, a combination with means for heating the oil in a restricted stream in a furnace, a reaction chamber connected thereto, means for reducing the temperature of the oil discharged from the reaction chamber,
  - 20 and means for maintaining pressures in excess of 500 pounds per square inch on the heating means, the reaction chamber and the cooling means, separate means for injecting gaseous material into the reaction chamber and into the cooling means, evaporating, dephlegmating and condensing means serially connected to the cooling means and means for reducing the pressure upon the oil undergoing treatment between the cooling and evaporating means.
  - 30 2. A process for the conversion of hydrocarbon oils comprising the steps of raising the oil to a cracking temperature in a heating zone, passing the heated oil to an enlarged reaction zone, directing the oil thence to a zone of reduced temperature, introducing to the oil in the reduced temperature zone, an oxygen bearing gas adapted to react with the oil while maintaining the pressure in excess of five hundred pounds per square inch upon the oil undergoing treatment, and cooling the charging oil in said reduced temperature zone by circulating oil to be treated in indirect heat exchange relation therewith.
  - 40 3. A process for the conversion of hydrocarbon oils comprising raising the oil to a cracking temperature in a heating zone, passing the heated oil to an enlarged reaction zone, passing the oil from said reaction zone to a zone of reduced temperature in which
  - 45 the oil is maintained at a temperature materially below 700° F. and substantially in the liquid phase, introducing an oxygen containing gas into said reaction zone to effect heating of the oil in said reaction zone, introducing an oxygen containing gas into the zone of reduced temperature to produce anti-knock hydrocarbon derivatives of oil, and cooling the oil in said reduced temperature zone to prevent the formation of undesirable reaction products.
  - 50 4. A process for the conversion of hydrocarbon oils comprising raising the oil to a cracking temperature in a heating zone, passing the heated oil to an enlarged reaction zone, introducing an oxygen containing gas into said enlarged reaction zone to maintain a high temperature therein, directing the oil from the reaction zone to a zone of reduced temperature in which the oil is maintained at a temperature materially below 700° F. and substantially in the liquid phase, introducing an oxygen containing gas into the oil in the zone of reduced temperature to produce anti-knock hydrocarbon derivatives of oil while maintaining the pressure in excess of five hundred pounds per square inch and cooling the zone of reduced temperature to prevent the formation of undesirable products.
  - 55 5. A process for the conversion of hydrocarbon oils, comprising the steps of raising the oil to a cracking temperature in a heating zone, passing the heated oil to an enlarged reaction zone, directing the oil thence to a zone of reduced temperature in which the oil is maintained at a temperature materially below 700° F. by an indirect heat exchange with the oil to be heated and substantially in the liquid phase and introducing into the oil in the reduced temperature zone an oxygen bearing gas adapted to react with the oil while maintaining the pressure in excess of 500 pounds per square inch upon the oil undergoing treatment to produce anti-knock hydrocarbon derivatives in the oil.
  - 60 6. A process for the conversion of hydrocarbon oils, comprising the steps of raising the oil to a cracking temperature in a heating zone, passing the oil to an enlarged reaction zone without cooling, reducing the temperature of the oil by passing it through a zone in an indirect heat exchange with the oil to be heated, supplying an oxygen bearing gas to the oil to produce anti-knock derivatives therein and maintaining upon the zones pressures in excess of 500 pounds per square inch, discharging the oil from the oxidizing stage into a zone of reduced pressure and distilling off the lighter fractions, refluxing the vapors evolved by such distillation and subjecting them to a final condensing action.
  - 65 7. A process for the conversion of hydrocarbon oils, comprising the steps of raising the oil to a cracking temperature in a heating zone, passing the oil to an enlarged reaction

zone without cooling, reducing the temperature of the oil by passing it through a zone in an indirect heat exchange with the oil to be heated, supplying an oxygen bearing gas 5 to the oil to produce anti-knock hydrocarbon derivatives therein and maintaining upon the zones pressures in excess of 500 pounds per square inch, discharging the oil from the oxidizing stage into a zone of reduced pressure, 10 and distilling off the lighter fractions, refluxing the vapors evolved by such distillation and recycling the refluxed condensate through the system for retreatment, and subjecting the uncondensed vapors to a final 15 condensing action.

8. A process for the conversion of hydrocarbon oils, comprising the steps of raising the oil to a cracking temperature in a heating zone, passing the oil to an enlarged reaction 20 zone without cooling, discharging the oil from the reaction zone into a zone of reduced temperature in which the oil is maintained at a temperature materially below 700° F. and substantially in liquid phase by an indirect 25 heat exchange with the oil being supplied to the system, supplying an oxygen bearing gas to the oil in the reduced temperature zone to produce anti-knock hydrocarbon derivatives therein and maintaining upon the 30 zones pressures in excess of 500 pounds per square inch, discharging the oil from the reduced temperature zone into a zone of reduced pressure and distilling off the lighter fractions, refluxing the vapors evolved by 35 such distillation and subjecting them to a final condensing action.

9. A process for the conversion of hydrocarbon oils, comprising the steps of raising the oil to a cracking temperature in a heating 40 zone, passing the oil to an enlarged reaction zone without cooling, reducing the temperature of the oil by passing it through a zone in an indirect heat exchange with the oil to be heated, supplying an oxygen bearing 45 gas to the oil in the reduced temperature zone to produce anti-knock derivatives therein and maintaining upon the zones pressures in excess of 500 pounds per square inch, discharging the oil from the reduced temperature 50 zone into a zone of reduced pressure, adding heat to the zone of reduced pressure to assist in the distillation of the volatile fractions from the liquid hydrocarbons, distilling off the lighter fractions, refluxing the vapors 55 evolved by such distillation and subjecting them to a final condensing action.

10. A process for the conversion of hydrocarbon oils comprising heating the oil to a conversion temperature, maintaining the oil 60 at conversion temperature by introducing an oxidizing gas thereinto, passing the oil into a cooling and oxidizing zone, passing an oxidizing gas into contact with the oil continuously as it passes through said cooling and 65 oxidizing zone and simultaneously reducing

the temperature of the oil moving through said cooling and oxidizing zone, to that temperature at which oxidized hydrocarbons having anti-knock properties are formed, by passing feed oil in extended indirect heat exchange relation with the oil in said zone thereby maintaining the temperature sufficiently low to form the desired oxidized hydrocarbon derivatives. 70

11. A process for the conversion of hydrocarbon oils comprising heating the oil to a conversion temperature, maintaining the oil at conversion temperature by introducing an oxidizing gas thereinto, passing the oil into a cooling and oxidizing zone, passing an oxidizing gas into contact with the oil continuously as it passes through said cooling and oxidizing zone and simultaneously reducing the temperature of the oil moving through said cooling and oxidizing zone, to that temperature at which oxidized hydrocarbons having anti-knock properties are formed, by passing feed oil in counter-current 80 indirect heat exchange relation with the oil in said zone thereby maintaining the temperature sufficiently low to form the desired oxidized hydrocarbon derivatives. 85
